(57) **CLAIM**

The ornamental design for a support head for video-photographic apparatus, as shown and described.

DESCRIPTION

FIG. 1 is a top perspective view of a support head for video-photographic apparatus, showing my new design;

FIG. 2 is a front view thereof;

FIG. 3 is a rear view thereof;

FIG. 4 is a right elevation view thereof;

FIG. 5 is a left elevation view thereof;

FIG. 6 is a bottom view thereof; and,

FIG. 7 is a top view thereof.

The broken lines in the drawings are intended to show environmental structure or boundaries that form no part of the claimed design.
